UNITED STATES PATENT OFFICE.

IDA BLANCHE URQUHART, OF TORONTO, CANADA.

DESIGN FOR A SHOE AND FLEXIBLE GAITER.

SPECIFICATION forming part of Design No. 34,616, dated June 4, 1901.

Application filed March 2, 1901. Serial No. 49,663. Term of patent 7 years.

To all whom it may concern:

Be it known that I, IDA BLANCHE URQUHART, a subject of the King of Great Britain, residing at the city of Toronto, in the county of York, Province of Ontario, Canada, have invented and produced a new and original Design for a Shoe and Flexible Gaiter, of which the following is a specification, reference being had to the accompanying drawing, forming part thereof.

The drawing is a perspective view of my invention.

In the drawing, A is a shoe, and B the gaiter, which is shaped as a half-stock to the form of a leg to a point just above the swell of the calf. The line between the gaiter-top and the shoe is marked by the braid C. The front of the gaiter has scallops of braid D, formed

thereon in imitation of the scalloped edges of the overlapping upper of a boot-top. A series of buttons are placed up this portion of the gaiter, so as to give the whole the appearance of a cloth-topped boot.

Having described my invention, what I claim as new, and desire to secure by Letters Patent, is—

The design for a shoe and flexible gaiter as herein shown and described.

In testimony whereof I have signed my name to this specification in the presence of two subscribing witnesses.

IDA BLANCHE URQUHART.
